DISPENSING DEVICE

George Boden, Waterbury, Conn., assignor to
Scovill Manufacturing Company, Waterbury,
Conn., a corporation of Connecticut

Application July 19, 1933, Serial No. 681,068

6 Claims. (Cl. 312—74)

This invention relates to dispensing devices and more particularly to devices for dispensing articles mounted on elongated carrier strips or tapes such, for example, as pins or the like. In numerous industries, clothing factories, laundries and other places where articles of clothing are handled, it is customary to fold each piece of clothing and pin it together so as to retain the form in which it is folded. This requires the constant picking up of relatively small pins either from a loose mass or from a supporting tape, an operation which is difficult and tends to delay the work.

An object of this invention is to provide a dispenser for articles of the type set forth, constructed and arranged to enable the operator to seize such articles one at a time rapidly and easily without requiring any particular thought or care on the operator's part.

20 This and other objects which will be apparent to those skilled in this particular art are accomplished by the invention hereinafter described, certain embodiments of which are illustrated in the accompanying drawings in which,

25 Fig. 1 is a top plan view of a pin dispenser constructed in accordance with one embodiment of this invention;

Fig. 2 is a similar view of part of the mechanism shown in Fig. 1 illustrating the parts in another position;

Fig. 3 is a side elevation of the elements shown in Fig. 2;

Fig. 4 is a similar view with parts broken away;

Fig. 5 is a sectional view on the line 5—5 of Fig. 3;

Fig. 6 is a top plan view of a dispenser constructed in accordance with another embodiment of this invention;

Fig. 7 is a side elevation, partially broken away, of the operating parts showing the operation of the ejector in placing a pin in position to be seized;

Fig. 8 is a similar view with the parts in a different position;

Fig. 9 is a transverse sectional view on the line 9—9 of Fig. 8;

Fig. 10 is a view similar to Fig. 8 looking from the opposite side; and

Fig. 11 is a sectional view on the line 11—11 of Fig. 8.

50 The present invention is adapted for use in dispensing pins or the like from the usual paper strip or tape in which they are customarily mounted. For large consumers long lengths of such tapes holding several hundred pins are provided in the form of a relatively large supply roll. The present invention comprises a support for rotatably holding such a large roll and a simple, rugged mechanism associated with the support for drawing the strip from the roll and intermittently feeding it so as to place the ar-

ticles in the strip successively in position to be readily seized by the operator.

The invention comprises a base 10 having a centrally located upwardly projecting pin 11 adapted to rotatably support a supply roll 12 of 5 paper tape or strip 13 having articles such as pins 14 mounted thereon in the usual way. A dispensing mechanism 15 is supported on the base adjacent the supply roll and, in the modification shown in Figs. 1 to 5, comprises an elongated, hollow, upright guide 16 through which the strip 13 and supported articles are fed by a feeding pawl 17 which may be formed as shown by a spring arm mounted on an actuator plate 18 and extending through a longitudinal slot 19 formed 10 in the adjacent wall of the guide 16, to successively engage the articles or pins 14 within the guideway, as best shown in Fig. 5. The actuator 18 is supported on a pivot 20 for swinging movement toward and from the guide. A holding 20 pawl 21 is secured to the guide 16 and projects inwardly through the slot 19 to prevent retrograde movement of the strip 13.

It will be apparent that when the actuator plate is moved from the position shown in Fig. 5 25 to the position shown in Fig. 2, the end of the spring pawl 17 moves the strip longitudinally through the guide 16 by engagement with one of the supported pins. The spring pawl 17 is so tensioned as to normally return the actuator 30 plate 18 to the position shown in Fig. 5 against the stop 22. This outward movement of the actuator retracts the pawl to engage the next 35 following article in the strip 13, retrograde movement of the strip being prevented by the holding pawl 21.

The construction of the parts is such that the pins are successively placed in position just beyond the exit end of the guide 16, as shown in Figs. 3 and 4. The actuator plate 18 is operated 40 ordinarily by the thumb of the worker who places his forefinger on the upper end of the guide 16 and moves the actuator from the position shown in Fig. 5 to that shown in Fig. 2 by pressing it with his thumb. This feeds a pin into position 45 to be seized and simultaneously and automatically brings the worker's thumb and forefinger together upon the pin head. The act of withdrawing the pin from the strip releases the actuator which is returned to the position shown in 50 Fig. 5 by the spring feeding pawl 17.

In the modifications shown in Figs. 6 to 11, the dispensing mechanism comprises an elongated, hollow, upright guide 26 through which the strip 13 and supported articles 14 are fed 55 by a feeding pawl 27 extending through a longitudinal slot 28 formed in the adjacent wall of the guide to successively engage articles on the strip and feed the latter through the guide 26 as best shown in Fig. 8. The pawl is actuated 60

by toggle links 29, one of which is connected to a pivot 30 and the other of which is connected to a vertically movable actuator 31 supported on a pivot 32 adjacent the rear of the guide 26, as shown in Fig. 10. A spring 33 normally holds the actuator in its upper position, as shown in Figs. 8 and 10. A holding pawl 34 is secured to the guide 26 and projects inwardly through the slot 28 to prevent retrograde movement of the strip 13. The actuator 31 has a perforated presser plate 35 by means of which it is depressed from the position shown in Figs. 8 and 10 to that shown in Fig. 7. An article ejecting lever 36 is pivotally mounted beneath the actuator 31 and is normally held in ineffective position shown in Figs. 8 and 10 by a leaf spring 37.

It will be apparent that operation of the actuator 31 by swinging it downwardly about its supporting pivot from the position shown in Figs. 8 and 10 to that shown in Fig. 7 will retract the feeding pawl 27, the strip 13 being held against retrograde movement in the guide by the holding pawl 34. When the actuator is released the spring 33 returns it to the position shown in Figs. 8 and 10 and this movement produces a feeding movement of the pawl 27 to move the strip 13 longitudinally through the guide 26 and feed the leading pin into the position shown in Figs. 8 and 10, where it is just in advance of the exit end of the guide. When the presser plate 35 of the actuator is next pressed downwardly it will be apparent that the lower edge of the actuator engages the adjacent rear end of the pivoted ejector 36 so as to raise the forward pin-engaging end thereof, as indicated in Fig. 7, striking the lower end of the pin or other article and partially ejecting it from the strip through the perforation in the finger plate, so that its head projects above such plate in position to be seized by the worker. The arrangement of the presser plate 35 is such that the worker ordinarily presses the same downwardly with his thumb and forefinger on opposite sides of the perforation. This automatically causes the pin which is raised by the ejector 36 to be positioned between the thumb and finger of the worker. The act of withdrawing the pin from the strip releases the actuator 31 which returns to the position shown in Fig. 8, and such return movement on the part of the actuator causes the feeding pawl 27 to feed another pin into position to be dispensed.

It will be apparent that the invention can be variously modified within the scope of the appended claims.

55 I claim:

1. A dispenser for articles mounted on strip material comprising in combination, a guide through which said strip passes, a feeding pawl operative to feed said articles successively into position to be seized, means preventing retrograde movement of said strip in said guide, a manually operated actuator for said feeding pawl arranged to enable the operator to seize an article upon operation of said actuator, and means operated by movement of said actuator for partially ejecting an article from said strip into position to be seized.

2. A dispenser for articles mounted on strip material comprising in combination, a guide through which said strip passes, a feeding pawl operative to feed said articles successively into

position adjacent the end of said guide, means for preventing retrograde movement of said strip in said guide, a spring pressed manually operated actuator for said feeding pawl, a toggle operated by said actuator to move said pawl, and means for partially ejecting from said strip the article adjacent the end of said guide to be seized. 5

3. A dispenser for articles mounted on strip material comprising in combination, a slotted 10 guide through which said strip passes, a feeding pawl operative through the slot in said guide to feed said articles successively into position adjacent the end of said guide, means for preventing retrograde movement of said strip in said guide, 15 and a manually operated actuator for said feeding pawl including a perforated presser plate, and means operated by movement of said actuator for partially ejecting an article from said strip through the perforation in said presser plate into 20 position to be seized.

4. A dispenser for articles mounted on strip material comprising in combination, a slotted guide through which said strip passes, a feeding pawl operative through the slot in said guide to 25 feed said articles successively into position adjacent the end of said guide, means preventing retrograde movement of said strip in said guide, a manually operated actuator for said feeding pawl pivotally associated with said guide and arranged to enable the operator to seize an article upon operation of said actuator, and a pivotally mounted ejector lever positioned so as to be operated by said actuator to partially eject an article from said strip into position to be seized. 35

5. A dispenser for articles mounted on strip material comprising, in combination, a flat base, a pin mounted on said base for rotatably holding a supply roll of material thereon, a dispensing and feeding mechanism mounted on said base at 40 one side thereof and spaced from said pin a distance sufficient to clear a supply roll on said pin, including an elongated guideway carried by said base through which the article holding strip from said supply roll passes, said guideway having a 45 slotted wall, a feeding pawl supported adjacent said wall and extending through the slot into strip feeding position and having its operative end guided by said slot, and a finger actuated, pivotally mounted plate for operating said pawl to 50 feed said strip, said plate being pivoted to swing relative to said base about an axis perpendicular to the direction of feed of the strip and being located to swing to a position at which the operator's fingers may naturally come into article 55 gripping position at the end of the guideway upon operation of the device.

6. A dispenser for articles mounted on strip material comprising in combination a slotted 60 guideway through which said strip passes, a pivotally mounted plate adapted to be swung toward and from said guideway by pinching it against the edge of said guideway and an article feeding pawl actuated by movement of said plate, for feeding said articles successively into a position 65 at which the operator's fingers may naturally come into article gripping position upon operation of the device to be seized by the operator pinching said plate and guideway together.
